US0D1067889S

(12) **United States Design Patent** (10) **Patent No.:** **US D1,067,889 S**
(45) **Date of Patent:** **** Mar. 25, 2025**

(54) **REMOTE CONTROL**

(71) Applicant: **Alcon Inc.**, Fribourg (CH)

(72) Inventors: **Alejandro Garfio**, Mission Viejo, CA (US); **Andrew Zoolakis**, Carlsbad, CA (US); **Brandon L. Spoelstra**, Trabuco Canyon, CA (US)

(73) Assignee: **Alcon Inc.**, Fribourg (CH)

(**) Term: **15 Years**

(21) Appl. No.: **29/911,176**

(22) Filed: **Aug. 30, 2023**

(51) LOC (15) Cl. **14-03**

(52) U.S. Cl.

USPC **D13/168**

(57) **CLAIM**

The ornamental design of a remote control as shown and described.

DESCRIPTION

FIG. 1 is an isometric view of the remote control of the present invention.

FIG. 2 is a top view of the remote control of the present invention.

FIG. 3 is a first side view of the remote control of the present invention.

FIG. 4 is a second side view of the remote control of the present invention.

FIG. 5 is a bottom view of the remote control of the present invention.

FIG. 6 is a front view of the remote control of the present invention; and,

FIG. 7 is a rear view of the remote control of the present invention.

The broken lines in the drawings indicate portions of the remote control that form no part of the claimed design.

1 Claim, 5 Drawing Sheets
